UNITED STATES PATENT OFFICE.

CLINTON D. MORRIS, OF BINGHAMTON, NEW YORK.

GARMENT AND HAT HANGER.

1,142,451.

Specification of Letters Patent. Patented June 8, 1915.

Application filed January 23, 1913. Serial No. 743,722.

To all whom it may concern:

Be it known that I, CLINTON D. MORRIS, a citizen of the United States, residing at Binghamton, in the county of Broome and 5 State of New York, have invented certain new and useful Improvements in Garment and Hat Hangers, of which the following is a specification.

My invention relates to an improvement 10 in combined garment and hat holders, in which the entire set of garments of a suit, also a hat, may be hung together, and it has for its object to provide a simple, inexpensive device for engaging the ends of a garment as well as supporting a hat and coat, 15 at the same time adapted to hold a coat, vest and trousers and hat, simple in construction and inexpensive to manufacture, also adapted to hold waists, skirts and an 20 entire costume.

With this object in view my invention consists in certain novel features of construction and arrangement of parts as will be hereinafter fully described and pointed out 25 in the claims, reference being had to the accompanying drawings in which—

Figure 1 is a perspective view of my device. Fig. 2 is a vertical section taken on the line 2, 2 of Fig. 1 and Fig. 3 is a plan 30 view of my device.

The same reference characters denote like parts in each of the several figures of the drawing.

In carrying out my invention, I provide a 35 curved cross bar A, conforming to the lines of the shoulders of a coat or vest. Pivottally mounted in bar A, I have the vertical hanging hook, F. Extending downward from the under side of the bar A and mounted 40 therein I have the metallic spring rods B B and B' B' so as to spread outward at their lower ends. On the lower ends of rods B B and B' B' are mounted the parallel bars C and C'. Slidably mounted on the spring 45 rods B and B and B' and B', I have the handle bar D. The spring bars B and B and B' and B' pass through openings in said handle bar D at the points 2, 2 and 2' 2'. Mounted on the side of bar A I have 50 screw eyes, 3, 3 and linked in these screw eyes 3, 3 is the loop hook E.

In the operation of my device I raise the handle bar D sliding it along the spring rods B B and B' B' toward the top. The 55 resilient nature of the spring rods cause the

bars C and C' to spread and I then insert an article of clothing between the bars C and C'. I then pull down the handle bar D which draws together the bars C and C', 60 holding or clamping the garment firmly in place. The hanging hook F is pivotally mounted and turns so that the hanger may be fastened on a wire or cord at any angle. When I desire to use the loop hook E for a 65 hanger, I so turn the hang wire F that the loop hook E will pass over the wire F until it rests upon and is supported by the bar A and assumes the position shown in Figs. 1 and 2. When not used as a hat hanger, the 70 loop hook E is turned upon the rear side of the bar A, as shown in broken lines in Fig. 2, and in that position does not interfere with objects near the side of the hanger.

Having thus described my invention, what 75 I claim as new and for which I desire Letters Patent is as follows:

1. In a device of the class described, a supporting bar, a hanger for the supporting bar rotatably mounted in the latter at one end 80 and having a hook at its free end, a hat hook pivotally secured at one end to the rear side of the supporting bar and adapted to be swung over and rest upon the supporting bar, said hat hook being formed with an 85 opening to permit the hat hook to be swung over and embrace the supporting hanger when the latter has been turned so that its hook is disposed in the same direction as the opening in the hat hook. 90

2. In a device of the class described, comprising a supporting bar a hanger for the supporting bar rotatably mounted in the latter at one end and having a hook at its other end normally disposed in the same direction as the supporting bar, a hat hook formed of spaced parallel members pivotally secured at one end to the rear side of the supporting bar and adapted to be swung over and rest upon the supporting bar, the 100 hook of the hanger having been turned at right angles to the supporting bar to permit the parallel members of the hat hook to pass upon opposite sides of the hanger. 95

In testimony whereof I have affixed my 105 signature in presence of two witnesses.

CLINTON D. MORRIS.
